US00D755718S

(12) **United States Design Patent**
Wu

(10) **Patent No.:** **US D755,718 S**
(45) **Date of Patent:** **** May 10, 2016**

(54) **VIBRATION GENERATOR WITH CLAMPING FIXTURE**

(71) Applicant: **CHUAN LIANG INDUSTRIAL CO., LTD.**, Taichung (TW)

(72) Inventor: **Jung-Chun Wu**, Taichung (TW)

(73) Assignee: **CHUAN LIANG INDUSTRIAL CO., LTD.**, Taichung (TW)

(**) Term: **14 Years**

(21) Appl. No.: **29/503,467**

(22) Filed: **Sep. 26, 2014**

(51) LOC (10) Cl. **13-01**

(52) U.S. Cl.

USPC **D13/114**

(57) **CLAIM**

The ornamental design for a vibration generator with clamping fixture, as shown and described.

DESCRIPTION

FIG. 1 a perspective view of a vibration generator with clamping fixture showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines shown represent unclaimed subject matter and form no part of the claimed design.
